UNITED STATES PATENT OFFICE

WILBUR FRANCIS CRAWFORD, OF WACO, TEXAS

SHIPPING CONTAINER

Application filed February 26, 1931. Serial No. 518,541.

This invention relates to shipping jackets especially adapted for use in connection with such perishable commodities as ice cream and milk.

5 Briefly stated, an important object is to provide a shipping jacket of the character suggested in which the closure arrangement thereof is simplified as compared with other jackets intended for the same purpose, first to 10 provide improved insulation, second to facilitate the introduction of a can of ice cream or the like into the jacket and third to reduce the cost of manufacture.

Another object is to provide a shipping 15 jacket of the type alluded to which, by reason of the simplified closure arrangement, has an improved appearance enhancing the marketability of the jacket.

Other objects and advantages will be apparent during the course of the following description.

In the accompanying drawing forming a part of this application and in which like numerals are employed to designate like parts 25 throughout the same,

Figure 1 is a side elevation of the improved shipping jacket, parts being shown in section,

Figure 2 is a top plan view of the improved jacket,

20 Figure 3 is a bottom plan view of the improved jacket,

Figure 4 is a fragmentary perspective of the jacket, the view illustrating the sealing flaps thereof in open position.

25 Figure 5 is a fragmentary side elevation illustrating the upper portion of the jacket, the view being partly in section and at right angles to the showing in Figure 1.

In the drawing wherein for the purpose of 30 illustration is shown a preferred embodiment of the invention, the numeral 5 designates a tubular body embodying inner and outer layers of canvas or other suitable material between which there is confined an insulating layer 6 of horse hair, felt or other material having the insulating qualities necessary in a jacket of the kind disclosed. The inner and outer layers of fabric and the intervening layer of insulating material 6 may

35 be stitched together as indicated at 8 or other- wise joined. The stitching 8 may extend both circumferentially and longitudinally of the jacket or be arranged in any other manner found expedient.

55 In manufacture, the bottom 10 of the jacket may be strengthened and reinforced by a boot 12 of a material having the wear resisting and insulating qualities desirable in a shipping jacket for perishables such as ice cream and milk.

60 Referring now to the closure arrangement for the jacket, attention is invited to Figure 4 illustrating that there is a single outer flap 16 of rectangular formation secured for the full width thereof to the upper end of one side wall of the body 5 or constituting an extension of such side wall. The area of the flap 16 is slightly greater than the area of the upper end of the body 5 and the dimensions of the flap are such that when the flap 65 is in the closed position shown in Figure 1, it will entirely close the mouth of the jacket with the otherwise free end of the flap resting upon the otherwise free upper end of the opposite side wall of the body.

70 The construction of the outer sealing flap may correspond substantially to the construction of the body portion of the jacket and is provided on the under surface thereof and at a point spaced in from the sides and ends thereof with a pad like member 20 having a length and width to snugly fit within the upper end of the jacket. With the depending portion 20 of the flap 16 thus snugly received within the upper portion of the jacket, the end and edge portions of the flap will have engagement with the adjacent portions of the side walls of the jacket to cooperate with the portion 20 in providing a substantially fluid 75 tight seal between the flap and the body of the jacket. In this connection, it might be noted that the material forming both the body 5 and the flap 16 are necessarily pliable so that when brought together, especially under force, the contacting surfaces of these parts 80 will come together and provide an approximately fluid tight seal preventing the incursion of outside air into the jacket.

85 As might otherwise be expressed, the flap 16 has the under side thereof rabbeted to de- 90 95 100

100

fine a central plug-like portion adapted to fit snugly within the jacket and a marginal or flange portion by which the flap is engaged with the upper end of the jacket. The flap 16 may be provided at suitably spaced points with straps 24 adapted to be connected with buckles or other fastening devices 26 secured to the sides of the jacket. It is a simple matter to draw the end and edge portions of the flap 16 into firm pressure contact with the upper end of the jacket to provide a substantially fluid tight contact between these parts.

As shown in Figures 1, 2 and 4, the body 5 is provided with a pair of oppositely located outer flaps 28 secured at their inner ends thereof to opposite side walls of the body or formed integral with such side walls. The outer flaps 28 are of a length equal to or slightly greater than the distance half way across the inner flap 16 so that the flaps 28 overlap when brought into closed position by the straps 30 and the co-acting buckles 32. The straps 30 may be secured by riveting or otherwise to the outer surface of one of the flaps 28 while the buckles 32 may be secured to the other flap 28.

In practice, a can of ice cream or a container for any other perishable commodity may be placed within the jacket and, as will be recognized, it is intended that the jacket shall be constructed for special use in connection with various kinds of commodities, due regard being had for the nature of the commodity to be shipped and the dimensions of the container in which the commodity is placed.

With the container thus placed snugly within the jacket, the inner flap 16 is brought into closed position with the plug or pad portion 20 thereof closely fitted within the mouth of the jacket. The outer flaps 28 may now be brought into overlapping relation with each other and overlying relation with the inner flap 16 and when the straps 24 and 30 are secured in place, as shown in Figure 1, the upper end of the jacket will be sealed effectively against the entrance of outside air into the jacket so that it is possible by the use of the improved jacket to ship such perishable commodities as milk and ice cream for rather long distances without the possibility of spoilage.

As previously suggested, the arrangement of the flaps is such that the entrance of an ice cream can or the like into the jacket is facilitated and in this connection attention is invited to Figure 4 in which it is illustrated that one side of the mouth of the jacket is entirely free and it is over this side that the can may be introduced into the jacket. The arrangement of the flaps and the manner of connecting the same to the upper ends of the jacket is such that the flaps will remain in open position until intentionally closed and thus the flaps will not interfere with the entrance of a commodity container into the jacket or the removal of the container therefrom.

A three flap arrangement as shown in the drawing has an improved appearance as compared with the four flap arrangement, in other jackets for the same purpose, and thus the marketability of the jacket is enhanced. Also, the three flap arrangement provides for the more expeditious and economical manufacture and has superior wear resisting qualities commanding its use in connection with the shipment of a variety of commodities.

Figure 5 illustrates that one side of the jacket 5 may be provided with a handle 34 of any flexible material found adaptable for the purpose, the ends of the handle being secured in any suitable manner to the jacket.

It is to be understood that the form of invention herewith shown and described is to be taken merely as a preferred example of the same and that such minor changes in arrangement and construction of parts may be made as will remain within the spirit of the invention and the scope of what is claimed.

Having thus described the invention, what is claimed is:

1. In a shipping jacket, a tubular body of insulating material and having side walls, an inner flap secured to the upper end of one of said side walls, the entire upper end of the opposite side wall of said body being free for engagement by the outer end portion of said inner flap and to facilitate the introduction of a commodity container into said tubular body, the under side of the flap being provided with a depending portion spaced inward from the edges of the flap and snugly received within the upper portion of the tubular body, means to secure said inner flap in closed position with the depending lower portion thereof within the tubular body, and a pair of outer flaps secured to the upper ends of the other side walls of the tubular body and having means by which the same may be secured in overlying relation to said inner flap.

2. In a shipping jacket, a tubular body of insulating material for the reception of a commodity container and having side walls, a single inner flap secured to the upper end of one of said side walls, the entire upper end of the opposite side wall of said jacket being free for engagement by the outer end portion of said single flap and unobstructed to facilitate the introduction of a commodity container into said tubular body, the under side of said single flap being provided at points spaced in from the sides and ends thereof with a plug-like pad adapted to be snugly received within the tubular body, and a pair of outer flaps secured to the other side walls of the tubular container and adapted to overlie the single inner flap, said outer flaps being provided with cooperating fastening

means holding the outer flaps firmly over said single inner flap.

3. In a shipping jacket, a tubular body of insulating material for the reception of a commodity container and having side walls, a single inner flap secured to the entire upper end of one of said side walls, the upper end of the opposite side wall of said jacket being free for engagement by the outer end 10 portion of said single flap and to facilitate the introduction of a commodity container into said tubular body, the under side of said single flap being provided at points spaced in from the sides and ends thereof with a 15 plug-like pad adapted to be snugly received within the tubular body, cooperating means carried by said inner flap and body to secure said flap in closed position, and a pair of outer flaps secured to the other side walls of 20 the tubular container and adapted to overlie the single inner flap, said outer flaps being provided with cooperating fastening means holding the outer flaps firmly over said single inner flap.

25 4. In a shipping jacket, a tubular body of insulating material for the reception of a commodity container and having side walls, a flap carried by the upper end portion of one of said side walls, the entire upper end 30 portion of the opposite side wall of said body being free for engagement by the outer end portion of said flap and to facilitate the introduction of a commodity container into said tubular body, additional flaps carried by 35 the upper end portions of the other side walls of said body approximately at right angles to said first named flap, said first and second named flaps being arranged for overlapping relation, and releasable fastening means for 40 securing said first and second-named flaps in overlapping relation.

5. In a shipping jacket, a tubular body of insulating material for the reception of a commodity container and having side walls, 45 a single inner flap secured to the upper end of one of said side walls, the entire upper end of the opposite side wall of said body being free for engagement by the outer end of said inner flap and to facilitate the introduction of a commodity container into 50 said tubular body, a pair of outer flaps secured to the upper ends of the other side walls of the tubular body and positioned to overlie said inner flap, and releasable fastening means for securing said outer flaps in 55 overlying relation to said inner flap.

In testimony whereof I affix my signature.
WILBUR FRANCIS CRAWFORD.
